PAPER FILE

Robert J. Aston, Pittsburgh, Pa.

Application April 6, 1938, Serial No. 200,523

6 Claims. (Cl. 129—4)

This invention relates to paper files, and its general object is to provide a device of that character, which is primarily designed for holding and securing the pages of newspapers, magazines, and like periodicals together, so that they can be conveniently read, and without possibility of the pages becoming relatively separated or falling apart.

A further object is to provide a paper file that can be easily and expeditiously applied and removed with respect to the pages, and includes means that not only sets up a clamping action against the pages, but penetrates the same, so that the pages are not only held together but casual displacement or removal of the device is practically impossible.

Another object is to provide a paper file that includes clamping and penetrating means which are enclosed and therefore protected against damage or breakage.

A still further object is to provide a device of this character, that is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view of the device which forms the subject matter of the present invention when not in use or in normal position.

Figure 2 is a similar view, with the device in use.

Figure 3 is a longitudinal sectional view taken through the device when arranged as shown in Figure 1.

Figure 4 is a longitudinal sectional view taken through the device with the parts in operative position, as shown in Figure 2.

Figure 5 is a fragmentary perspective view illustrating the clamping jaws and the relative parts thereof.

Figure 6 is a fragmentary perspective view taken from the opposite side of Figure 5.

Figure 7 is a sectional view taken on line 7—7 of Figure 3.

Figure 8 is a sectional view taken approximately on line 8—8 of Figure 4.

Referring to the drawings in detail, it will be noted that my device includes a housing made up of a tubular body member 1, and tubular end members 2 which are slidably mounted on the tubular body member for telescopic association therewith, and the body and end members are each provided with slots 3 extending longitudinally thereof and for registration with each other. The ends of the body members are open, while the outer ends of the end members are closed by caps 4 of rounded formation with slots therein registering with the slots 3 of the body and end members, for cooperation therewith for receiving the folded edge portions of the pages of a newspaper or the like A, as indicated in Figure 2.

Fixed to the tubular body member 1 and along one longitudinal edge of the slot thereof is a stationary jaw 5 of elongated formation and the jaw is of a length to extend beyond the body member. Cooperating with the jaw 5 is a movable jaw 6 which is co-extensive with the length of the jaw 5 and the jaws have their outer ends outwardly flared as at 7 to prevent the ends from damaging the pages, as will be apparent. Secured to the stationary jaw 5 are pins 8 mounted in openings in the movable jaw for guiding the latter toward and away from the jaw 5 in its movement, for clamping and releasing the pages. The pins are arranged adjacent to the inner longitudinal edge of the jaws, to provide ample clamping space for the pages, as will be apparent upon inspection of Figure 8, which shows the jaws in clamping position while in Figure 7, the jaws are in released position.

In order to move the jaw 6 toward and away from the jaw 5, I provide a cam strip 9 which is substantially co-extensive with the length of the jaw 6, and is secured midway its ends thereof, as at 10. The outer ends of the cam strip are bent at right angles inwardly toward the jaw 6 and the right angle bent ends 11 are fixed to the jaw 6, so that the strip 9 from its central connection with the jaw 6 is inclined outwardly toward the outer ends thereof.

The outer ends of the end members 2 each have secured thereto one of the ends of pairs of guide fingers 12 and 13, and the guide fingers 12 are disposed diametrically opposite the guide fingers 13, but the guide fingers 12 cooperate with each other for a different purpose than that of the guide fingers 13, although the guide fingers are identical in construction, and each have their inner ends bent outwardly at right angles.

- angles upon themselves as at 14 for engagement with the body member 1 upon opposite sides thereof, as clearly shown in Figures 3 and 4. The guide fingers 12 are mounted for slidable movement on the inclined cam portions of the strip 9, and are connected thereto by collars 15 which are fixedly secured to fingers 12. By that structure, it will be obvious that upon movement of the tubular end members 2 outwardly from each other, that the movable jaw 6 will be moved toward the jaw 5 for clamping association therewith, but upon inward movement of the end members 2 the jaw 5 is moved away from the jaw 6. That movement is brought about by the inclined cam portions of the cam strip 9 and the fact that the guide fingers 12 are connected thereto and the right angle bent ends 14 thereof engage the inner surface of the body member 1.
- 20 The page penetrating means of my device includes a spring strip 16 that is fixed midway its ends to the stationary jaw 5, as at 17, and has its ends bent at right angles thereto and inwardly for movement through openings 18 arranged in the jaws 5 and 6 adjacent their ends, as best shown in Figures 3 and 4. The bent ends 19 of the spring strip 16 are of triangular formation to provide penetrating points, and the guide fingers 13 are slidably mounted on the spring strip 16 for moving the penetrating ends 19 into and out of the openings 18, it being obvious that the penetrating ends 19 extend through the openings when the jaws are in clamping association, as shown in Figure 4 and the ends 19 are withdrawn from the openings, when the jaws are spaced, as shown in Figure 3. The guide fingers 13 are connected to the spring strip 16 by collars 20 which are fixedly secured to the fingers 13.
- 40 From the above description and disclosure of the drawing, it will be obvious that my device not only includes clamping jaws for setting up a clamping engagement against the pages A, for holding the latter together in book form so that they can be conveniently read, but the pages are likewise held by the penetrating ends 19, which also prevents casual displacement or removal of the device from the pages, in that the penetrating ends pass through the pages when the latter is clamped between the jaws, as will be obvious upon inspection of Figures 2 and 4.
- 55 It is thought from the foregoing description that the advantages and novel features of the invention will be readily apparent.
- 55 It is to be understood that changes may be made in the construction and in the combination and arrangement of the several parts, provided that such changes fall within the scope of the appended claims.
- 60 What I claim is:
1. A paper file comprising a housing having a paper receiving slot therein, paper clamping means within the housing, and slidably mounted means included in the housing structure and connected to the clamping means for disposing the latter into and out of clamping association.
  2. A paper file comprising a housing having a paper receiving slot therein, paper clamping

means within the housing, paper penetrating means within the housing and cooperating with the clamping means for securing the pages of a paper together, and slidably mounted means included in the housing structure and connected to the clamping means for disposing the latter into and out of clamping association.

3. A paper file comprising a housing having a paper receiving slot therein, paper clamping means within the housing, paper penetrating means within the housing, and slidably mounted means included in the housing structure and connected to the clamping means and the penetrating means for operating the same.

4. A paper file comprising a tubular housing 15 having a paper receiving slot therein and including a body member, end members telescopically mounted on the body member and closing the ends thereof, an elongated jaw fixed to the body member, an elongated jaw mounted for movement toward and away from the stationary jaw for cooperation therewith, paper penetrating means mounted for movement within the body member, and means connecting the end members to the movable jaw and penetrating means for 25 operating the same upon movement of the end members.

5. A paper file comprising a tubular housing including a tubular body member and end members telescopically mounted thereon for slidable 30 movement, caps on the end members for closing the ends of the housing, said body and end members having registering paper receiving slots therein and extending longitudinally thereof and through the caps, an elongated jaw member fixed 35 to the body member and extending from one edge of the slot thereof, an elongated jaw mounted for movement in the body toward and away from the stationary jaw for cooperation therewith, means for guiding the movable jaw with respect 40 to the stationary jaw, said jaws having outwardly flared outer ends, means connecting the end members to the movable jaw for operating the same upon movement of the end members, and paper penetrating means mounted on the 45 stationary jaw.

6. A paper file comprising a housing including a tubular body member and tubular end members telescopically mounted on the body member for slidable movement, said members having registering paper receiving slots therein, caps closing the outer ends of the end members and having the slots extending therethrough, a jaw fixed within the body and extending through the ends thereof, a jaw mounted for movement toward 55 and away from the stationary jaw for cooperation therewith and being co-extensive with the length thereof, said jaws having outwardly flared outer ends, a cam strip fixed to the movable jaw, a spring strip fixed to the stationary jaw and 60 having free ends terminating in paper penetrating means, and means connected to the end members and slidably mounted on the cam strip and spring strip for simultaneously operating the movable jaw and penetrating means upon movement of the end members.

ROBERT J. ASTON.
